UNITED STATES PATENT OFFICE.

JOHN COMMERFORD, OF COLUMBUS, OHIO.

DESIGN FOR A CAR-BODY.

SPECIFICATION forming part of Design No. 23,206, dated April 17, 1894.

Application filed February 28, 1894. Serial No. 501,873. Term of patent 14 years.

2. *all whom it may concern:*

Be it known that I, JOHN COMMERFORD, a citizen of the United States, residing at Columbus, in the county of Franklin and State of Ohio, have invented and produced a new and original Design for Car-Bodies; and I do hereby declare the following to be a full, clear, and exact description of the same, reference being had to the accompanying drawing, forming a part thereof.

In the accompanying drawing, I illustrate a perspective view of the car body made according to my design.

The design consists of a car body having the vertical walls A with their upper parts outwardly inclined as shown at B, and the standards C on the sides of the car fitting un-

der said outwardly inclined parts B and extending downward therefrom toward the bottom of the car body. The outer edges or surfaces of the standards C are flush or in a plane co-incident with the edges of the outwardly inclined parts B.

What I claim, and desire to secure by Letters Patent, is—

The design for a car body substantially as herein shown and described.

In testimony whereof I affix my signature in presence of two witnesses.

JOHN COMMERFORD.
